[57] CLAIM

The ornamental design for a body massage attachment for a handheld showerhead, as shown and described.

DESCRIPTION

FIG. 1 is a perspective view of a body massage attachment for a handheld showerhead showing my new design;

FIG. 2 is an elevational view taken from one side thereof, the opposite side being a mirror image of the side shown;

FIG. 3 is a front elevational view thereof;

FIG. 4 is a top plan view thereof;

FIG. 5 is a rear elevational view thereof; and

FIG. 6 is a cross-sectional view taken along line 6—6 in
FIG. 5.
